E. S. STIMPSON,
FEELER MECHANISM FOR LOOMS.
APPLICATION FILED DEC. 26, 1919.

Patented June 7, 1921.

UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,380,939.

Specification of Letters Patent.

Patented June 7, 1921.

Application filed December 26, 1919. Serial No. 347,322.

To all whom it may concern:

Be it known that I, EDWARD S. STIMPSON, of Hopedale, in the county of Worcester and State of Massachusetts, have invented a 5 new Feeler Mechanism for Looms, of which the following is a specification.

The present invention is an improvement upon the feeler mechanism set forth in United States Letters Patent No. 1,309,226, 10 July 8, 1919, and consists in a new feeler tip.

In the type of laterally slipping feeler disclosed in said patent, it is important that the teeth of the feeler tip should cling to 15 the weft so as to prevent premature side slipping under all conditions of the weft winding. Unless this is the case the bobbins may be ejected while still carrying a large amount of weft. At the same time, 20 the teeth must freely and with certainty slip along the bare bobbin so that the functional side slip will take place when demanded. Also, the tip organization should be such that the weft will not be cut and 25 that the bobbin will not be scratched or marred.

It is also important that the feeler tip itself should be readily attached to and removed from the feeler arm. The feeler tip 30 is subject to a succession of rapid blows continuously repeated and hence wears out and requires replacement. It has been common to attach a feeler tip to a feeler arm by means of a screw but such screws are liable 35 to jar loose, so that other means of attachment are desirable.

The present improvements consist in a readily attachable and detachable feeler tip not requiring the employment of a screw 40 or any other separate attaching device, and this tip is provided with an improved tooth construction which adequately clings to the weft when in contact therewith, and slips reliably upon a bare bobbin without scratch- 45 ing or marring the same.

The improvements are illustrated in the accompanying drawings, in which—

Figure 1, is a plan view of the feeler mechanism. Fig. 2, is a plan view of the 50 feeler tip on an enlarged scale showing the same engaged by the weft on the bobbin. Fig. 3, is a plan view of the feeler tip on an enlarged scale illustrating the side slip of the feeler tip on the bare surface of the bob-

bin. Fig. 4, is a vertical section in the plane 55 indicated by the line 4—4 in Fig. 2. Figs. 5 and 6 are detail views of the feeler tip detached. Figs. 7 and 8 are detail views of the rear end of the feeler arm illustrating its construction which enables the feeler 60 tip to be readily attached to and detached therefrom.

The side slipping feeler arm A, is similar in construction and mode of operation to that of the feeler arm set forth in the said 65 Patent No. 1,309,226. The present improvements relate solely to the feeler tip B, and the means for connecting it to the feeler arm.

The feeler tip B is made of spring sheet 70 steel which is bent into shape to straddle the rear end of the feeler arm, and the bend of the tip is cut to constitute the teeth D. This construction is illustrated in Figs. 5 and 6. The sheet steel is first cut in shape 75 to produce the illustrated form of the feeler tip and it is then bent upon itself to form the upper and lower legs 10 and 11. It is desirable, as shown in Fig. 4, that the two legs should be inclined toward each other, 80 with their ends nearer together than the legs are at the uniting bend. With this construction, it is necessary to spread the free ends of the legs apart to slip the tip upon the feeler arm. Then, when the feeler arm 85 is in place, as shown in Fig. 4, the resilience of the metal of the tip causes the legs to grip the feeler arm frictionally and snugly.

One of the legs is formed with inwardly 90 extending locking studs 12 formed by forcing the metal of the leg inwardly as illustrated in Figs. 4, 5 and 6. As shown, it is the lower leg 11 which is provided with the locking studs. These projections coöperate with recesses 13 in one side of the feeler arm, 95 as shown in Figs. 4 and 7. In case the locking studs are on the lower leg of the tip these recesses 13 are on the lower side of the feeler arm, as shown in Fig. 9. To facilitate the engagement of the studs and recesses the 100 feeler arm is formed with a tapering longitudinal groove 14. This groove extends from the forward recess 13 rearwardly to the extreme rear end of the feeler arm, and intersects the rear recess 13, as shown in 105 Fig. 7. This groove widens and deepens from the forward recess 13 to the rear end of the feeler arm, as shown in Figs. 4 and 7.

The depth of the groove at the rear end of the feeler arm is approximately equal to the height of the studs 12 above the upper surface of the lower tip leg 11. The feeler tip is placed upon the arm A by slipping it endwise upon the rear end of the arm. The open ends of the legs are sprung apart so as to straddle the rear end of the arm. The tip is then pushed forwardly so that the studs 12 successively enter the deep mouth of the groove 14. The studs as they follow the shallowing groove during the forward push of the feeler tip spread the legs apart until both studs register with their respective recesses whereupon the projections snap into the recesses owing to the resilience of the tip. It will be noted that the recesses are conical and the studs are hemi-spherical, so that when both studs register with their respective recesses there is a close fit between each stud and its recess. Accordingly, the tip is firmly and securely held upon the feeler arm. At the same time, these shapes of the recesses and studs render it simple for the leading projection to ride past the rear recess as the tip is slid into place.

During the running of the loom, there is no danger of the tip being displaced on the arm. The blows of the weft upon the bobbin are in the same direction as the movement which unites the tip with the arm. Accordingly, there is no tendency for these blows to displace the tip. Since there is a plurality of spaced locking studs on the tip coöperating with correspondingly spaced recesses in the feeler arm any tendency to skew the tip on the arm during the lateral slip of the arm is effectually resisted. The union between the tip and the arm is due to the presence of reciprocally and mutually engaging integral locking studs and recesses formed in the parts themselves; and, accordingly, there is no extraneous or separate fastening elements such as a screw which might work loose and permit the tip to become accidentally detached.

Nevertheless, when the tip is so worn that it should be removed, it is easily detached from the feeler arm. By spreading apart the two resilient legs of the tip, the studs 12 are readily disengaged from the recesses 13 and the tip can then be removed. No special tools are required to either attach or remove the tip.

The uniting bend between the two legs of the tip is substantially semi-cylindrical with the axis of the cylinder extending horizontally and parallel with the axis of the bobbin G and the axis on which the lay T swings. The rear end of the feeler tip is thus convex toward the weft H and bobbin, as shown in Fig. 4, so that the blow of the weft upon the tip gives the effect of depressing the mass of the weft as exaggeratedly

shown in Fig. 4. The weft engaging teeth D are formed at the rear end of the tip by slits 15 cut in the rear bent end of the tip. There is a plurality of these slits, as illustrated so that several teeth are formed. These slits 15 are inclined with respect to the upper and lower surfaces of the tip, as shown in Fig. 6, and the slits are such as would be made with a saw with flat parallel sides. The result is that each tooth D is blunt along horizontal lines, it is pointed along vertical lines due to the curvature of the rear end of the tip, it is inclined between top and bottom, and it has square edges.

Also, as illustrated in Figs. 2 and 3, the rear end of the tip is curved along horizontal lines so that the rear ends of the teeth are arranged in a horizontally extending arc of a circle, so that the rear ends of the teeth are at varying distances from the cylindrical surface of the bobbin, as illustrated in Fig. 3. In the normal position of the feeler arm, shown in Figs. 1 and 2, the middle teeth of the tip are nearer the axis of the bobbin than the teeth at either end of the horizontally extending arc. The effect of this tooth construction is that the teeth sink into the mass of the weft along both horizontal and vertical lines as exaggeratedly shown in Figs. 2 and 4, respectively. Hence, when weft is present the teeth cling to the weft and prevent the feeler arm moving laterally under the impact or forward push of the bobbin. The teeth cannot cut the weft because the teeth are blunt and because they extend diagonally so that no one tooth can enter between parallel convolutions of the weft on the bobbin.

At the same time, when the bobbin is bare where it contacts with the tip, the tip slips laterally along the bare surface due to the impact of the bobbin, as illustrated in Fig. 3. This slipping takes place with certainty and without any scratching or marring of the bobbin.

Fig. 1, illustrates the weft just making initial contact with the feeler tip, and also the parts of the feeler mechanism which immediately coöperate with the feeler arm. This coöperating feeler mechanism is the same as that of the aforesaid Patent No. 1,309,226, and hence requires but brief reference. The feeler arm A is mounted on a bracket I, attached to lateral extension J of the breast beam. A rock shaft K is journaled to the forward end of the bracket turning on a vertical axis. This rock shaft has a through aperture through which the front end of the feeler arm extends and slides. Toward its rear end the feeler arm extends through a broad passageway in the bracket, the margins of this passageway being indicated by the dotted lines L, L. The top of this passageway is closed by a cap M, which with the bottom of the bracket confines the

feeler arm against vertical movement. Secured to the feeler arm near its middle is a slide N which slides on horizontal ways O, of the bracket. A spring Q surrounds the 5 feeler arm between the slide N and rock shaft K, and normally holds the feeler arm in its rearward position with the slide against the shoulders of the bracket which support the cap M. The feeler arm is also 10 maintained by the spring against the outer (left hand) wall L of the rear passageway. The rock shaft K is offset laterally and outwardly with respect to the rear passageway so that the feeler arm stands at an angle to 15 the fore and aft swing of the lay and the bobbin (or the weft thereon) and encounters the tip along a fore and aft path nearer the tip of the bobbin than a parallel path intersecting the rockshaft. So long as the weft on 20 the bobbin encounters the teeth of the tip the resistance thus offered prevents any side slipping of the tip lengthwise of the bobbin. Accordingly, as the lay moves forward after the first encounter of the weft with the tip 25 there is no slipping of the tip on the weft; but during the completion of the forward movement of the bobbin the feeler arm is moved forwardly compressing the spring Q. When the bobbin is bared opposite the feeler 30 tip, the feeler tip slips laterally to the right and this movement is utilized to set in action the train of weft replenishing mechanism.

This functional swing of the feeler arm 35 under the impact of the bare bobbin causes the feeler arm to encounter a controller X and move it laterally inward. This controller is mounted in a transverse guideway Y of the bracket J (shown in dotted lines) 40 and it has a slot Z (also indicated in dotted lines) through which the feeler arm passes. When the functional swing of the feeler arm is imparted to it the controller is slid laterally inward. This lateral movement of the 45 controller is utilized to bring about weft replenishment as explained in detail in the aforesaid patent. After replenishment has been initiated, the feeler arm is restored to its normal position as described in the afore- 50 said patent.

The arrangement of the feeler teeth extending diagonally from the top to the bottom of the feeler is not broadly claimed herein since such arrangement constitutes 55 the subject matter of my copending application for Letters Patent of the United States, Serial No. 401,943, filed August 7, 1920.

I claim—

1. A feeler arm having a plurality of recesses near its rear end and a longitudinally extending groove connecting said recesses and terminating at the rear end of the arm, 60

said groove increasing in depth and width from the foremost recess to the rear end of the arm, in combination with a feeler tip 65 consisting of resilient metal bent to form two legs straddling the rear end of the feeler arm and resiliently gripping the upper and lower faces thereof, one of said legs having on its inner face a plurality of inwardly projecting 70 studs corresponding in position to the recesses in the feeler arm and interlocking therewith, said studs being adapted to slide lengthwise along said groove in the feeler arm in attaching the tip to the arm. 75

2. A feeler arm having a plurality of recesses near its rear end and a longitudinally extending groove connecting said recesses and terminating at the rear end of the arm, said groove increasing in depth and width 80 from the foremost recess to the rear end of the arm, in combination with a feeler tip having legs straddling the rear end of the feeler arm, one of said legs having on its inner face a plurality of inwardly projecting 85 studs corresponding in position to the recesses in the feeler arm and interlocking therewith, said studs being adapted to slide lengthwise along said groove in the feeler arm in attaching the tip to the arm. 90

3. A feeler arm having a plurality of recesses near its rear end in combination with a feeler tip straddling the rear end of the feeler arm, one of said legs having on its inner face a plurality of inwardly projecting 95 studs corresponding in position to the recesses in the feeler arm, and interlocking therewith.

4. A feeler arm and a resilient detachable tip sprung into place upon the arm and 100 locked thereto by mutually engaging coacting integral studs and recesses on said arm and tip.

5. A bent metal feeler tip having the bend at its rear feeling end, said bend having a 105 plurality of teeth arranged in a horizontally extending arc of a circle, said teeth being constituted by diagonally extending slits in the bent rear end of the feeler tip, whereby diagonal teeth are formed having blunt rear 110 ends and square edges.

6. A bent sheet metal feeler tip having the bend at its rear feeling end, said bend having a plurality of teeth arranged in a horizontally extending arc of a circle, said teeth 115 being constituted by slits cut diagonally in the bent rear end of the feeler tip.

7. A feeler arm and a resilient detachable tip straddling said arm and locked thereto by mutually engaging coacting integral 120 studs and recesses.

In witness whereof I have hereunto signed my name.

EDWARD S. STIMPSON.
